UNITED STATES PATENT OFFICE

2,542,389

COMBINED IGNITION TIMER AND FUEL INJECTION UNIT

John J. Broderick, Springfield, Mass., assignor
to American Bosch Corporation, Springfield,
Mass., a corporation of New York

Application November 9, 1946, Serial No. 708,833

4 Claims. (Cl. 123—139)

1

This invention relates to fuel injection apparatus and ignition apparatus for internal combustion engines and more particularly to an ignition timer and fuel injection pump unit which may be readily mounted upon the engine and which has a single drive connection therewith.

An object of the invention is to provide a combined fuel injection pump and ignition timer unit for internal combustion engines.

Another object of the invention is to provide such a unit which is interchangeable on existing engines with the ignition timing apparatus whereby such engines may be readily adapted for utilizing fuel injection to replace the carburetion system of such engines.

Another object of the invention is to provide a new and improved unit which comprises the ignition timing apparatus together with a fuel injection unit which meters, distributes and injects the fuel and which unit may be readily mounted on existing engines in place of the ignition timing and distributing means previously employed.

Another object of the invention is to provide a new and improved low cost, fuel injection pump for gasoline, spark ignition engines.

Another object of the invention is to provide a new and improved fuel injection unit for use on engines which is applicable to existing engines embodying carburetors with minimum changes and utilizing a single drive connection with which the engine is already provided for both ignition timing and fuel injection.

Other objects and advantages of the invention will be apparent from the following description taken in connection with the accompanying drawings. It will be understood that many changes may be made in the details of construction and arrangement of parts without departing from the invention as set forth in the accompanying claims, the preferred form having been given by way of illustration only.

Referring to the drawings:

Fig. 1 is a side view of an ignition timing and fuel injection pump unit embodying the invention;

Fig. 2 is a top or plan view thereof;

Fig. 3 is a sectional view taken on line 3—3 of Fig. 1 looking in the direction of the arrows;

Fig. 4 is a sectional view taken on line 4—4 of Fig. 3 looking in the direction of the arrows;

Fig. 5 is a fragmentary, sectional view taken on line 5—5 of Fig. 4 looking in the direction of the arrows; and

2

Fig. 6 is a fragmentary, sectional view taken on line 6—6 of Fig. 4 looking in the direction of the arrows.

The advantages of employing fuel injection systems rather than the conventional carburetor on engines have become so well known that it is not believed necessary to state them all here. The principal advantages of such systems are increased power, greater economy, broader fuel range, that is, the possibility of using cheaper grades of fuel with less tendency for detonation, and increased performance.

It is the principal object of the present invention to provide means whereby such fuel injection system may be incorporated in existing carburetor type engines with minimum changes and at relatively economical installations by the provision of a new, combined ignition timing means and fuel injection apparatus adapted to be readily mounted upon the engine and be driven by the conventional engine drive already provided for driving the conventional ignition timing apparatus.

Referring more particularly to the drawings, wherein similar reference characters designate corresponding parts throughout the several views, the device embodying the invention includes a housing 1 having an open lower side which is adapted to be closed by the cover member 2 which is secured to the housing 1 by screws or the like 3 of suitable size and number and said cover 2 is provided with the integral tubular shank 4 adapted to fit within the recess or socket which is provided in conventional gasoline engines for receiving the drive of the ignition timing apparatus. The shank 4 provides a bearing for the drive shaft 5 which extends through the distributor sleeve 9 in the housing 1 and through the shank 4 and is connected by gearing, not shown, with a rotatable part of the engine, preferably the valve operating shaft in the conventional manner.

Adjacent the upper end portion of the housing 1 is provided the housing member 7 adapted to contain the conventional ignition timing apparatus adapted to be operated by a cam, not shown, carried on the reduced extension 8 of the shaft 5.

The shaft 5 has the helical groove 9 adapted to draw excess lubricant from the gear chamber 10 out of said chamber and into the engine crankcase. Opening 11 is provided for external lubrication of the unit. The shaft 5 is also provided with the gasket ring 12 to prevent the lubricant from entering the electrical compartment.

One end of a vacuum line (not shown) is connected to the outlet 13, which is connected to the peripheral groove 14, and said vacuum line is connected at its other end to the intake manifold to draw out any fuel leaking in the direction of the electrical compartment and which might otherwise reach the electrical compartment.

The plunger drive gear 15 is keyed to the shaft 5 by the key 16 and said gear is adapted to be rotated upon rotation of said shaft and to simultaneously rotate the plunger drive pinion 17 which is in mesh therewith and which is provided with the reduced shank 18 which carries the plunger drive shoe 19 which is eccentrically positioned in a hole or groove in the upper end of said shank 18 and adapted to be rotated upon rotation of said pinion 17 and shank 18.

As shown in Fig. 6, the shank 18 is rotatably mounted in the eccentric sleeve 19b having the reduced extension 19a adapted to be engaged at 20 its opposite sides by the set screws 20 and 21 for adjusting the angular position of said shank 18 and thereby adjusting the position of said shoe 19 for the purpose hereinafter described.

The housing 1 is provided with a series of radially spaced holes 22, one of which is provided for each combustion chamber adapted to receive fuel from the fuel injection pump. While as shown in Fig. 3, the present invention is provided with six such outlets and is, therefore, adapted for a six-cylinder engine, the pump could be adapted for two, four, six or eight outlets as desired. The pump is adaptable for manifold injection, which is the intention of the pump shown in the drawings, but it will be understood that the pump could also be adapted for cylinder injection.

Each of the outlets 22 is provided with a port or groove 23 adapted to connect its respective outlet 22 with the distributing groove 24 in the distributing sleeve 6 successively upon rotation of said sleeve 6 which is keyed to the shaft 5 as shown in Fig. 3 and adapted to rotate therewith.

The distributor sleeve 6 may be constructed of molded nylon or other suitable material.

The housing 1 is also provided with the fuel inlet 25 adapted to be connected to a fuel line from a fuel supply tank and a throttle valve is provided for controlling the amount of fuel fed to the pumping unit. If a booster pump is employed in the fuel line between the supply tank and injection pump, an outlet 25a may be connected to a return line to the fuel supply tank. The throttle valve comprises the valve 26 in the restricted opening 27 and said valve 26 is adapted to be controlled by the spring 28 and lever 29 which is pivotally mounted at 30 on the cover 31 which is secured to the housing 1 by screws or the like 32. The valve 26 extends through an opening in the diaphragm 33 and is secured thereto by means of the enlarged head portion 34 and nut 35 which is threaded on the valve member and adapted to be tightened against said diaphragm 33 to retain the parts in assembled relation.

Fuel reaching the pump enters the fuel supply chamber 36 from which it passes through the restricted opening 27 and ports 37 to the plunger bore 38 containing the double ended plunger element having the pumping portions 39 adjacent its opposite ends and the central reduced portion 40 adapted to receive the plunger drive shoe 19 which operates against the opposite shoulders 41 and 42 of said reduced central portion to reciprocate said plunger in the plunger bore 38 upon rotation of

4
said pinion 17 and shank 18 as previously described.

By adjusting the reduced extension 19a on the eccentric sleeve 19b by means of the set screws 20 and 21, one of which is loosened and the other tightened, it is possible to adjust the position of the shoe 19 and thereby adjust the plunger in mid position along its axis to reduce the quantity of fuel pumped on one end and simultaneously increase the quantity of fuel pumped on the other end of said plunger and thereby equalize the distribution of fuel to all outlets.

From the plunger bore 38 the fuel is pumped through the ports 43 and 44 alternately as each of the pumping portions of the plunger operates on its pumping stroke and said fuel reaches the check valves 45 and 46. The seat 45a for the valve 45 is shown in full and the valve seat 46a for the valve 46 in section and these valves are operated alternately as fuel reaches the valves through the ports 43 and 44 and the force of the fuel operates to move the valves against the action of the spring 47, so that fuel may pass through the central openings 48, as shown in the valve seat 46a, and reach the inclined ports 49 and 50 through which it passes to the distributing groove 24 as shown in Fig. 3 and from which it is distributed to its proper outlet. The ports 49 and 50 are inclined and connect groove 24 with check valves 45 and 46 respectively.

By utilizing a single common spring for the check valves 45 and 46 of which it is desirable to employ a minimum number, it is possible to obtain a single unit acting as a check valve to both plunger ends thereby equalizing the quantity of fluid distributed to each of the outlets 22.

The outlets 22 are each connected by suitable pipe lines to a respective fuel injection nozzle which is positioned in an opening in the manifold or cylinder to thereby provide fuel for the operation of the engine.

It will be seen that with the present invention that by replacing the conventional ignition timing apparatus of a conventional gasoline engine such as a bus or truck engine with the ignition timing and fuel injection apparatus of the present invention and by replacing the carburetor type manifold with a fuel injection type manifold that it is possible to readily convert such engine from a carburetor type engine to a fuel injection type engine with all the benefits of such type of engine as set forth above and that the present invention may be readily connected to the single drive already provided on the engine for operating the ignition timing apparatus.

From the foregoing it will be seen that I have provided simple, efficient and economical means for obtaining all of the objects and advantages of the invention.

Having described my invention, I claim:

1. In a device of the character described, a fuel ejection pump comprising a bore, a double ended plunger in said bore, drive means and means intermediate said pumping ends of said plunger and operatively connected with said drive means for reciprocating said plunger in said bore, a single distributing means operated by said drive means for distributing fuel from said fuel injection pump, fuel passageways from adjacent the opposite ends of said bore to said distributing means, check valve means in each of said passageways intermediate said pump and said distributing means and a single spring engaging said check valve means adjacent its ends and operating said check valve means.

2. In a device of the character described, a fuel injection pump, comprising a bore and double ended plunger adapted to reciprocate in said bore, a shaft, gear means operatively connected to said shaft, an eccentric operated by said gear means for reciprocating said plunger in said bore, means for supplying fuel to said bore means surrounding said shaft for distributing fuel pumped by said pumping plunger and fuel passageways from adjacent the opposite ends of said bore to 10 said distributing means.

3. In a device of the character described, a unit including ignition timing means for a circuit breaker and a fuel injection pump, said unit being adapted to supply ignition and fuel to an internal combustion engine, said fuel injection pump comprising a housing having a bore and a double ended plunger pumping element in said bore, a shaft driven by the engine for operating said circuit breaker and fuel injection pump, a distributor sleeve on said shaft and rotatable upon rotation of said shaft, a fuel passageway from said pump to said distributing sleeve, said distributing sleeve surrounding said shaft and having distributing means thereon and cooperating with spaced outlets in said housing for distributing fuel received from said injection pump, and means operatively connected to said shaft for operating said pumping plunger of said fuel injection pump, said means comprising gear means operated by said shaft, pinion means operated by said gear means, an eccentric on said pinion means and engaging said plunger for reciprocating said plunger in said bore and means associated with said pinion means for adjusting 25 said plunger along its axis to control the quantity of fuel supplied by each of the pumping ends of said plunger.

4. In a device of the character described, a

unit including ignition timing means for a circuit breaker and a fuel injection pump, said unit being adapted to supply ignition and fuel to an internal combustion engine, said fuel injection pump comprising a housing having a bore and a double ended plunger pumping element in said bore, a shaft driven by the engine for operating said circuit breaker and fuel injection pump, a distributor sleeve on said shaft and rotatable upon rotation of said shaft, a fuel passageway from said pump to said distributing sleeve, said distributing sleeve surrounding said shaft and having distributing means thereon and cooperating with spaced outlets in said housing for distributing fuel received from said injection pump, and means operatively connected to said shaft for operating said pumping plunger of said fuel injection pump, said means comprising gear means operated by said shaft, pinion means operated by said gear means, an eccentric on said pinion means and engaging said plunger for reciprocating said plunger in said bore.
